(57) **CLAIM**

The ornamental design for an electrical connector as shown and described.

DESCRIPTION

FIG. 1 is a front view of an electrical connector showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is front top right perspective view thereof;

FIG. 8 is a rear top left perspective view thereof;

FIG. 9 is a front view of an alternative embodiment of an electrical connector showing my new design;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is front top right perspective view thereof;

FIG. 16 is a rear top left perspective view thereof;

FIG. 17 is a front view of another alternative embodiment of an electrical connector showing my new design;

FIG. 18 is a rear view thereof;

FIG. 19 is a left side view thereof;

FIG. 20 is a right side view thereof;

FIG. 21 is a top view thereof;

FIG. 22 is a bottom view thereof;

FIG. 23 is front top right perspective view thereof; and,

FIG. 24 is a rear top left perspective view thereof.

(Continued)

The broken lines represent unclaimed portions of the electrical connector and form no part of the claimed design.

1 Claim, 21 Drawing Sheets
